UNITED STATES PATENT OFFICE.

JAMES ARTHUR REAVELL, OF LONDON, ENGLAND.

ROTARY DRYING MACHINE.

Application filed November 12, 1923, Serial No. 674,305, and in Great Britain February 28, 1923.

This invention relates to rotary drying machines and has for its object to improve that type of machine in which a heated drum picks up or has applied to its surface a liquid film of the material to be dried.

In rotary steam dryers previously employed, it has been customary to immerse the drying rollers within a bath of the liquid material to be dried. This has many disadvantages. Firstly, the ends of the drums become clogged and special scraping arrangements have to be provided for the purpose of removing the solidified material. A second difficulty is encountered by the liquid in the bath reaching a temperature due to contact with the drum which causes the liquor to boil and ultimately to coagulate. In another type of drier in which a film of liquid is introduced between two rollers there is the difficulty of maintaining a constant feed and the further necessity of having duplicate scrapers and conveyors to take the scraped material away.

According to the present invention a drying machine is provided comprising a rotary drum and a feed trough arranged along one side of the drum in such a manner as to deliver liquid to be dried onto the face of the drum the ends of the trough being preferably constructed to prevent overflow to the ends of the drum. Means are preferably provided for removing dried material in relatively small pieces from the side of the drum opposite to the feed trough. Agitating devices may be disposed in the feed trough and the dried material is removed preferably by a number of independently adjustable scraper blades so mounted as to be pressed into operative engagement with the surface of the drum by their own resiliency.

Reference will now be made to the accompanying drawings which illustrate, by way of example, constructions according to the invention and in which:—

Figure 1 is an elevation of the inlet side of a drying machine,

Figure 2 is an elevation of the removal side of the machine shown in Figure 1,

Figure 3 is a cross sectional elevation through the machine shown in Figures 1 and 2.

Figure 4 is a cross sectional elevation showing the adaptation of the machine shown in Figures 1-3 to vacuum drying, and

Figure 5 shows on a larger scale the method of mounting the scraper blades.

Referring first to Figures 1-3 the machine comprises a drum 1 having hollow trunnions 2 at its ends adapted to rotate in bearings 3 mounted on a fixed framework 4, one of the said trunnions being connected by suitable gearing with a prime mover. Through glands 5 in the outer ends of the trunnions are passed pipes 6 for the inlet and exhaust of a fluid medium for heating the drum. A feed trough 7 is mounted in the framework 4 and disposed parallel to the axis of rotation of the drum but below the horizontal plane of the said axis and the inner side of the trough adjacent the drum is constituted by a spring steel blade 8 which engages the drum throughout its length and prevents overflow of the substance under treatment to the space beneath the drum. The ends of the trough are constructed so as to engage closely the cylindrical surface of the drum near its edges and prevent overflow of any of the liquid under treatment onto the ends of the drum. With some types of liquid and especially with those whose solid content is liable to settle out, or again with liquids that will stratify, it may be necessary to employ an agitator. This consists of a rotatable shaft 9 passing through glands formed at the ends of the trough 7 and fitted with blades or paddles 10 which may be adjustable in position radially of the shaft. This agitating shaft is driven by chain and sprocket gear 11 from the driven trunnion 2.

To remove dried material from the surface of the drum 1, scraping devices are arranged on the side remote from the feed trough and comprise a number of thin blades or plates 12 secured by set screws 13 to a bar 14 extending from end to end of the framework 4 at a point below the horizontal plane of the axis of the drum, the blades 12 being slotted at 15 to allow adjustment relatively to the bar 14. Each scraper blade 12 is provided with one or more backing plates 16 and both blades and plates are preferably formed of stainless spring steel (see Figure 5). In mounting these elements the edges of the blades are caused to bear against the under surface of the drum to an extent sufficient to cause the blades to be slightly curved thereby enabling them to maintain a positive pressure contact with the surface of the drum by means of their

own resilience. The blades 12 are tapered in form so that their operative portions overlap and are preferably arranged as shown in Figure 2 with alternate blades in 5 advance of the remainder. The blades may be covered by a shield 17 the upper edge of which lies close to the surface of the drum and which is formed integral with or secured to a trough 18 into which the matter 10 removed by the blades falls and in which is disposed a worm conveyor 19 mounted on a shaft 20 carried in bearings in the ends of the trough 18 and provided with a pulley 21 for independent operation. The shield 17, 15 however, is not normally required but is only used for special materials. The trough 18 has an outlet 22 for dried material and may have jacket 23 for heating its contents when required, this jacket being connected by a 20 pipe 24 with the inlet pipe 6 by which fluid heating medium enters the apparatus, whilst the inlet to both pipes is controlled by a cock 25.

The operation of the apparatus above described is as follows:—

The solid matter in solution constituting the liquid to be dried is fed into the trough 7 from any definite source or the level of liquid in the trough may be kept practically constant by the employment of a float 30 valve interposed between the trough and a main supply tank. Rotation of the drum 1 in a clockwise direction, Figure 3, causes a film of liquid to adhere to the surface of the drum, the heat of which is regulated so 35 that it is sufficient to drive off the moisture in the film during a partial rotation. The scraper blades 12 each detach the hot dried material, the one in advance of the other so 40 that if the material does not of its own accord break up into fine particles when dry, the scraper blades themselves detach the material in broken ribbons or as fine scrapings which may be easily crushed. The dried 45 material thus detached by the scrapers is removed continuously by the conveyor 19 and discharged into suitable receptacles through the outlet 22.

The apparatus shown in Figure 4 is designed for use in vacuum drying in cases 50 where the material to be dried necessitates the removal of abnormal quantities of moisture or vapour. This apparatus is similar in general construction and operation to that shown in Figures 1 to 3 and similar reference 55 numerals have been used to indicate corresponding parts. The apparatus is enclosed wholly within a casing 26 having a flanged outlet 27 for connection to a condenser of 60 the surface or jet type, depending upon the requirements of the installation, and to a vacuum pump. The casing 26 is provided with glazed sight holes 28 and a socket for 65 the introduction of a feed pipe 29 arranged to admit the liquid to be treated to the outer

compartment 30 of a feed trough 31 which may be divided into two compartments by a partition 32 having weirs 33 formed at intervals throughout its length. At either or both ends of the trough 31 is a notch 34 communicating with an overflow pipe 35. The material detached from the surface of the drum by the scraper blades, which are arranged as in Figures 1-3, is deflected into the conveyor trough by plates 36 and 37 and an apron 38 75 extending downwardly from the bar 14 on which the scraper blades are mounted. The deflector plate 36 extends inwards nearly to the surface of the drum and serves to catch any material which is loosened, but falls 80 ahead of the scraper blades and to deflect such material back into the conveyor trough 18. In this form of the invention the worm conveyor trough communicates with a vacuum box or boxes, preferably two being employed so that as one is filled the valve leading to it is closed, the valve to the other box opened and the direction of movement of the conveyor reversed. In this manner one box can be emptied as the other is filled 85 and the operation of the apparatus is continuous.

In operation the partition 32 and weirs 33 serve to maintain a constant level of liquid in the inner compartment of the trough 31 95 so that the drying drum is supplied continuously with a uniform film of liquid.

The devices above described are capable of considerable modification without departing from the invention. For example, the feed trough may be movably mounted and adapted to be raised or lowered against the deciding level of a float valve or supply tank to regulate the feed of liquid to the heated drum. Furthermore, the scraper 105 blades may be arranged in various relative positions other than those shown and any type of conveyor capable of moving the dried material longitudinally of the trough 18 may be employed.

I claim:—

1. In a drying machine, a rotary drum, a feed trough for liquid material to be dried arranged along one side of said drum and having an upper edge engaging said drum below the level of the other edge of said trough, said drum forming a wall of said trough, and a plurality of independently adjustable staggered scraping devices for removing dried material from said drum. 115

2. A drying machine according to claim 1 wherein said scraping devices consist of independently adjustable scraper blades pressed into operative engagement with said drum by their own resilience. 120

3. A drying machine according to claim 1 wherein the scraping devices comprise a plurality of blades and backing plates, a bar fixed horizontally below the level of the axis of the drum, and set screws securing said 130

blades and backing plates to said bar, said blades being slotted to allow independent adjustment relatively to the bar.

4. In a drying machine a rotary drum, a feed trough for liquid to be dried arranged along one side of said drum and having an upper edge engaging said drum below the level of the other edge of said trough, said drum forming a wall of said trough, a bar 5 fixed horizontally below the level of the axis of said drum, a plurality of scraper blades

and backing plates, set screws securing said blades and backing plates to said bar, and slots in said blades for allowing independent adjustment of said blades relatively to said bar, said blades having staggered overlapping cutting edges and being pressed into engagement with said drum by their own resilience. 15

In witness whereof I affix my signature.

JAMES ARTHUR REAVELL.
